The ornamental design for a gas injection nozzle, as shown and described.

DESCRIPTION

FIG. 1 is a top, side, perspective view of a gas injection nozzle showing our new design;

FIG. 2 is a first elevational view thereof;

FIG. 3 is a second elevational view thereof;

FIG. 4 is a top plan view thereof; and,

FIG. 5 is a bottom plan view thereof.

Except for the threaded portion, all other elevational views are the same as FIGS. 2 and 3.

FIG. 2**FIG. 1****FIG. 4**

FIG. 3

FIG. 5
